UNITED STATES PATENT OFFICE

2,505,415

NAIL AND TACK MAKING APPARATUS

Louis Lukancic, Joliet, Ill.

Application November 19, 1947, Serial No. 787,007

2 Claims. (Cl. 22—77)

1

The present invention relates to new and useful improvements in apparatus for making nails, tacks and similar headed fastening devices.

An important object of the invention is to provide an apparatus of this character including a revolvable table having mold cavities in the surface thereof for receiving molten metal together with novel means for removing the molded articles from the cavities during continuous rotation of the table.

A further object of the invention is to provide a magnet supported above the table for withdrawing the molded articles from the cavities as the same pass under the magnet.

A still further object is to provide an apparatus of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view with parts broken away and shown in section.

Figure 2 is a top plan view.

Figure 3 is a fragmentary vertical sectional view through one side of the table taken on a line 3—3 of Figure 2.

Figure 4 is a transverse sectional view through the table taken on a line 4—4 of Figure 2.

Figure 5 is a fragmentary sectional view of the table taken on a line 5—5 of Figure 2, and

Figure 6 is an enlarged view in elevation of one of the molded articles.

Referring now to the drawings in detail wherein for the purpose of illustration I have disclosed a preferred embodiment of this invention, the numeral 5 designates a supporting structure generally composed of inner and outer annular walls 6 and 7 having rollers 8 supported at the upper edges thereof inwardly of the walls. The supporting structure is held in position on a foundation 9 by angle iron lugs 10.

An annular table 11 is mounted for rotation on the rollers 8 and is frictionally driven by one of the rollers having an electric motor 12 operatively connected thereto.

The table is provided with a plurality of tapering mold cavities 13 extending vertically therethrough, the cavities being countersunk at their upper ends as shown at 14 and the lower ends

2

of the cavities are open to provide a vent therefor.

A distributing box or receptacle 15 is supported in a stationary position above the table 11 by brackets 16 and molten metal is discharged into the distributor by means of a spout 17 extending from one side of a metal furnace 18 in which scrap metal is heated into a molten state.

A scraper 19 is supported beneath the table 11 adjacent the distributor 15 for removing metal projecting from the underside of the table through the vent openings of the cavities.

In the operation of the device, molten metal is discharged into the distributor 15 from the furnace 18 through the spout 17, the distributor 15 being open at its bottom for filling the cavities 13 with the molten metal as the cavities pass under the distributor during rotation of the table 11. Excess metal which solidifies by cooling and which projects from the underside of the table 20 is removed by the scraper 19.

The table 11 is rotated at a slow rate of speed to permit cooling of the metal before a complete revolution of the table and a magnet designated generally at 20 is supported in position above the table by a bracket 21 in a position for withdrawing the molded articles following the cooling and contraction thereof.

The magnet comprises a permanently magnetized drum 22 journaled at one end of the bracket 21, a non-magnetic drum 23 journaled at the center of the bracket in an elevated position and an endless non-magnetic belt 24 preferably of wire mesh material travelling over the drums. Transverse non-magnetic cleats 25 are suitably carried by the belt in spaced parallel relation to each other.

The drum 23 is provided with a pulley 26 at one end driven by a belt 27 from a motor 28 mounted at the other end of the bracket 21.

The magnetized drum 22 rotates close to the surface of table 11 at a point remote from the feeding distributor 15 and the table is rotated at a speed whereby the nails or other articles 29 molded in the cavities 13 of the table will be cooled before reaching the magnet and sufficiently contracted to be extracted from the cavities as they pass under the magnet. The magnet is rotated in a direction as shown by the arrow in Figure 5 whereby the nails are picked up and carried upwardly by the belt 24 and discharged into a suitable receptacle or chute (not shown) as they pass over drum 23. The cleats 25 prevent sliding of the nails downwardly on the inclined belt during travel thereof.

Having described the invention what is claimed as new is:

1. A nail making apparatus comprising a rotatable table having radially spaced apart mold cavities in the surface thereof, a heat reservoir containing molten metal disposed adjacent said table, a discharge spout extending from the reservoir and overlying said table, a radially extending distributor supported in a stationary position above the table and under the spout to feed molten metal to the cavities, a magnetic drum rotatably mounted above the table to remove molded articles from the cavities, a non-magnetic driving drum rotatably supported adjacent said magnetic drum and an endless non-magnetic foraminous belt entrained over said drums to receive at its reach entrained over the magnetic drum the molded articles and convey them away from the drum, said cavities having vent openings in their lower ends and a stationary scraper fixed adjacent the underside of the table to remove excess metal protruding through the openings.

2. A nail making apparatus comprising a rotatable table having radially spaced apart mold cavities in the surface thereof, a heat reservoir containing molten metal disposed adjacent said table, a discharge spout extending from the reservoir and overlying said table, a radially extending distributor supported in a stationary position above the table and under the spout to feed molten metal to the cavities, a magnetic

drum rotatably mounted above the table to remove molded articles from the cavities, a non-magnetic driving drum rotatably supported adjacent said magnetic drum and an endless non-magnetic foraminous belt entrained over said drums to receive at its reach entrained over the magnetic drum the molded articles and convey them away from the drum, said cavities having vent openings in their lower ends and a stationary scraper fixed adjacent the underside of the table to remove excess metal protruding through the openings.
